[57] **CLAIM**

The ornamental design for a rack for holding beverage order checks, substantially as shown and described.

DESCRIPTION

FIG. 1 is a perspective view of one form of a rack for holding beverage order checks showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a perspective view of another form of a rack for holding beverage order checks showing my new design;

FIG. 8 is a front elevational view thereof;

FIG. 9 is a rear elevational view thereof;

FIG. 10 is a right side elevational view thereof;

FIG. 11 is a left side elevational view thereof; and

FIG. 12 is a top plan view thereof.
